UNITED STATES PATENT OFFICE.

GEORGE W. BLAIR, OF PITTSBURG, PENNSYLVANIA.

DESIGN FOR A LAMP.

SPECIFICATION forming part of Design No. 19,718, dated March 25, 1890.

Application filed February 28, 1890. Serial No. 342,152. Term of patent 3½ years.

To all whom it may concern:

Be it known that I, GEORGE W. BLAIR, of Pittsburgh, in the county of Allegheny and State of Pennsylvania, have invented a new and original Design for Lamps, of which the following is a full, clear, and exact description.

My design consists in a lamp having the configuration and outline hereinafter described, and shown in the accompanying drawing.

The drawing illustrates a lamp and shade embodying my design.

The lamp-bowl A has a large spheroidal portion *a* and above it a conical zone *b*, an intervening shoulder *c*, and above the zone *b* a cylindrical portion *d*, with peripheral grooves *d'*. Below the portion *a* is a conoidal zone *e*. Below that is a smaller conoidal zone *f*, and be-

low that a spool-shaped portion *g*. At the foot is a portion *h* of the peculiar shape shown in the drawing. The shade *B* is of the shape illustrated, having a large conoidal part *i*, above it a cylindroidal portion *j* with flaring top, and below the part *i* is a zone *k*, and below that is a cylindriform zone *m*.

I claim—

The design for lamps, substantially as herein shown and described.

In testimony whereof I have hereunto set my hand this 19th day of February, A. D. 30 1890.

GEORGE W. BLAIR.
